HAT TREE

Filed March 24, 1928

Inventor:

Lester Thorndike Sawyer

Patented Jan. 1, 1929.

Des. 77,371

UNITED STATES PATENT OFFICE.

LESTER THORNDIKE SAWYER, OF FITCHBURG, MASSACHUSETTS.

DESIGN FOR A HAT TREE.

Application filed March 24, 1928. Serial No. 25,989. Term of patent 7 years.

To all whom it may concern:

Be it known that I, LESTER THORNDIKE SAWYER, a citizen of the United States, residing at Fitchburg, in the county of Worcester and State of Massachusetts, have invented a new, original, and ornamental Design for a Hat Tree, of which the following is a specification.

Reference is to be had to the accompanying drawing, forming part thereof.

The figure is a side elevation of a hat tree showing my new design.

I claim:

The ornamental design for a hat tree, as shown.

LESTER THORNDIKE SAWYER.
